UNITED STATES PATENT OFFICE.

JOHN J. DARNELL, OF INOLA, OKLAHOMA.

DESIGN FOR A FURNITURE ORNAMENT.

No. 39,997.

Specification for Design.

Patented May 18, 1909.

Application filed February 20, 1909. Serial No. 479,283. Term of patent 14 years.

To all whom it may concern:

Be it known that I, JOHN J. DARNELL, a citizen of the United States, residing at Inola, in the county of Rogers and State of Oklahoma, have invented a new, original, and ornamental Design for a Furniture Ornament, of which the following is a specification.

Reference is had to the accompanying drawing, in which the figure is a perspective view of a furniture ornament, showing my new and ornamental design.

I claim:

The ornamental design for a furniture ornament, as shown.

JOHN J. DARNELL.

Witnesses:

A. V. CHERRY,
CLEMENIA CHERRY.
